UNITED STATES PATENT OFFICE.

NATHAN AUSLANDER, OF PHILADELPHIA, PENNSYLVANIA.

CHRISTMAS-TREE HOLDER.

1,334,880.

Specification of Letters Patent. Patented Mar. 23, 1920.

Application filed January 26, 1920. Serial No. 353,927.

To all whom it may concern:

Be it known that I, NATHAN AUSLANDER, a citizen of the United States, residing at Philadelphia, in the county of Philadelphia, 5 State of Pennsylvania, have invented certain new and useful Improvements in Christmas-Tree Holders, of which the following is a description, reference being had to the accompanying drawing and to the figures of 10 reference marked thereon.

This invention relates to supports for Christmas trees and the like and more particularly to that type of holder provided with supporting legs pivoted intermediate 15 their length to a central spider adapted to support the butt of the tree, the upper ends of said supporting legs engaging the trunk of the tree to hold the same in position.

One of the objects of this invention is to 20 provide a device of the above character in which the supporting legs and the central spider are of the simplest construction and arranged to provide a holder of the minimum number of parts.

25 These and other objects will in part be obvious and will in part be hereinafter more fully disclosed.

Referring more particularly to the accompanying drawings:—

30 Figure 1 is a perspective view of one form of my improved holder showing the tree in dotted lines;

Fig. 2 is a plan view taken along line 2—2 of Fig. 1;

35 Fig. 3 is a perspective view of a modification of the structure shown in Fig. 1; and

Figs. 4 and 5 are enlarged detailed views of the pivotal connection for the legs.

The holder consists of three short metal 40 straps 1, 2 and 3, similar in all respects and each formed with the intermediate portions 4, 5, and 6 thereof arranged to form the adjacent sides of a triangular support for the butt of the tree. The outer or end portions 45 of each strap on each side of said intermediate portion are bent outwardly as at 7, 7', 8, 8', and 9, 9' to form pairs of spaced parallel supporting arms or members 10, 11 and 12, between which are pivotally mounted 50 three relatively long supporting legs 13, 14 and 15 in the form of metal straps. These straps are arranged with their broad faces outward so that their flat upper faces 16, 17 and 18 lie closely against the tree trunk 55 to present an extensive support therefor,

while the lower portion of said straps terminate in long sweeping curves outwardly and somewhat upwardly to provide the broad supporting feet 19, 20 and 21.

In that form of the device shown in Figs. 60 1 and 2, these relatively long thin straps, 13, 14 and 15 are twisted intermediate their length as at 22, 23 and 24, whereby the thin edges 25, 26 and 27 of the straps enter between the spaced parallel members 10, 11 65 and 12 of the spider and the broad faces of the straps which at this point, lie at right angles to its continuation at either side thereof, present wide surfaces to receive the pivotal pins 28, 29 and 30 passing through 70 registering holes in the supporting arms, and this face. This pivoting is preferably made by riveting but obviously any desirable detachable connection may be used. If desired, the upper trunk supporting portion 75 of the legs may be provided with holes to receive nails or screws to enter the tree trunk, and if desired, the curved supporting feet may be apertured for like purpose.

In that form of holder shown in Figs. 80 3, 4 and 5, instead of providing the supporting legs 31, 32 and 33 with an intermediate twist, the same are provided with eyelets riveted or otherwise fastened thereto, which eyelets are detachably bolted or riveted between the spaced parallel supporting arms 85 or members 10, 11 and 12.

It will be seen that a holder constructed as described is composed of members of the simplest form, of the fewest number of 90 parts, and arranged to provide a holder combining maximum supporting strength and durability with simplicity and cheapness of manufacture.

In forming the central brackets or spiders 95 4, 5 and 6 of short straps, the usual cast iron base is eliminated; by arranging these central straps as illustrated, the central portions thereof provide a most effective support for the butt of the tree while the spaced 100 parallel outer ends thereof form simple supporting arms for the legs or supporting straps 13, 14 and 15, the arrangement permitting the assemblage of all these members by means of three simple rivets 28, 29 and 105 30. In addition by forming the supporting legs 13, 14 and 15 of metal straps arranged with their broad faces outwardly, extensive supporting surfaces both at the tree trunk as at 16, 17 and 18 and at the curved feet 110

19, 20 and 21 are provided. By twisting these broad faces at the intermediate portions of the straps as at 22, 23 and 24 the narrow edge of the strap is presented between the supporting arms 10, 11 and 12 to provide a pivotal joint of maximum supporting strength.

It is obvious that minor changes in the details of construction may be made without departing from the spirit of the invention as set forth in the appended claims.

Having thus described the invention, what is claimed as new, is:—

1. A holder for Christmas trees and the like comprising three similar metal straps arranged with their intermediate portions forming the sides of a substantially equilateral triangle to provide a central support for said tree butt, said straps having their end portions bent outwardly from said central portions and arranged to form spaced parallel supporting members, a similar number of relatively long metal straps, each pivoted intermediate its length between two of said adjacent supporting members, each of said long straps having a relatively broad face and a relatively narrow edge and arranged with their broad faces outwardly facing to present extensive trunk engaging supports at the upper portions thereof, the lower ends of said straps being curved outwardly to form a substantial floor support, and the intermediate portion of each strap being twisted whereby the narrow edge of said strap is presented between the adjacent supporting members with the broad face thereof forming a support for the pivotal connection with said arms.

lower ends of said straps being curved outwardly to form a substantial floor support.

2. A holder for Christmas trees and the like comprising three similar metal straps arranged with their intermediate portions forming the adjacent sides of a substantially equilateral triangle to provide a central support for said tree butt, said straps having their end portions bent outwardly from said central portions and arranged to form spaced parallel supporting members, three relatively long metal straps, each pivoted betwixt its ends between two of said adjacent supporting members, each of said long straps having a relatively broad face and a relatively narrow edge and arranged with their broad faces outwardly facing to present extensive trunk engaging supports at the upper portions thereof, the lower ends of said straps being curved outwardly to form a substantial floor support, and the intermediate portion of each strap being twisted whereby the narrow edge of said strap is presented between the adjacent supporting members with the broad face thereof forming a support for the pivotal connection with said arms.

In testimony whereof I affix my signature.

NATHAN AUSLANDER.
